JOINT FORM FOR PAVING

Filed Jan. 23, 1930

FIG. 1.

FIG. 2.

FIG. 3.

Roscoe D. Farmer INVENTOR
By Loyal J. Miller, ATTORNEY

UNITED STATES PATENT OFFICE

ROSCOE D. FARMER, OF OKLAHOMA CITY, OKLAHOMA

JOINT FORM FOR PAVING

Application filed January 23, 1930. Serial No. 422,849.

My invention relates to forms for joints in concrete paving.

The objects of my invention are to provide a device of this class which is new, novel, 5 practical and of utility; which may be used on concrete paving or concrete paving base; which will form a straight line of cleavage in the top of the pavement thus causing any expansion breaks which might occur to follow a straight line; which will weaken the pavement vertically on said line of cleavage without disconnecting the pavement upon each side of the line; which may be used as a center strip longitudinally with the pavement and also for forming transverse joints; which will prevent the usual voids or honeycomb which occur in pavements adjacent the usual joint forms; which will permit the use of reinforcing steel across the joint; which 20 will provide a means for anchoring the reinforcing steel across such joints; which will save material over the usual joint form; which will thus save in freight and transportation expense; and, which will be efficient in accomplishing all the purposes for which it is intended.

At the present time it is the usual practice in forming pavement joints to use a vertical form which extends entirely through the pavement. The usual form is sometimes provided with a longitudinal groove or other deformity for breaking the vertical plane of cleavage, the object being to form a groove in the pavement on one side of the form, and a tongue on the other side registering with the groove. There is no communication provided for between the portions of pavement lying on each side of the form. Great care must be exercised in puddling the concrete on each side of the form in order to prevent voids being left in the concrete.

My form not only breaks the plane of cleavage in the usual manner, but also provides a communication of the concrete through the bottom portion of the form. It permits the laying of reinforcing steel through the form and also provides a means for anchoring the steel to the form and spacing it from the sub-grade.

With these and other objects in view as

will more fully appear, my invention consists in the construction, novel features, and combination of parts hereinafter more fully described, pointed out in the claims hereto appended, and illustrated in the accompanying 55 one-sheet drawing, of which,

Figure 1 is an elevational view showing a tie bar anchored through the form;

Fig. 2 is a fragmentary plan view of a pavement showing the form in place; and 60

Fig. 3 is a sectional view along the line 3—3 of Fig. 2.

Like characters of reference designate like parts in all the figures.

It is understood that various changes in 65 the form, proportion, size, shape, weight and other details of construction, within the scope of my invention may be resorted to without departing from the spirit or broad principle of my invention and without sacrificing any of the advantages thereof; and it is also understood that the drawings are to be interpreted as being illustrative and not restrictive.

One practical embodiment of the invention as illustrated in the drawings comprises:

A strip 1, of sheet metal or the like having a straight top edge 2, a longitudinal corrugation 3 lying below and paralleled with said edge 2, and a bottom edge 4. Cut upwardly in 80 said bottom edge 4, are a plurality of spaced beveled sided notches 5 their top straight edges 6 lying below and parallel with said corrugation 3. The portions of said strip 1 lying between said notches 5 form legs 7. 85

Each alternating one of said legs 7 is provided with a vertical corrugation 8 for strengthening the leg. Each other alternating one of said legs 7 is provided with a perforation 9, and slightly therbelow has a 90 square aperture 10 cut therethrough. The metal is not severed from strip 1 at the top of said aperture 10, but is turned outward at right angles to the plane of said strip 1. A portion of the outturned metal is cut transversely from each side as shown at 11 and its outer end portion is turned upward to form a clamp 12 for receiving a steel tie bar 13 projected through said perforation 9. Clamp 12 forms a means for attaching said 100

bar 13 in place during the pouring of the concrete. The direction in which said clamps 12 extend from said strip 1 is alternated upon each alternating leg 7.

5. In operation, strip 1 is placed vertically at the point where the joint is desired, with legs 7 resting upon the sub-grade. Bars 13 are inserted through perforations 9, and clamps 12 bent therearound with a pair of 10 pliers or the like. Should it be desired to use other reinforcing bars than said tie bars 13, such reinforcing bars may be inserted through apertures 10 and wired to bars 13 in a usual manner. The portion of legs 7 lying 15 between the bottom of apertures 10 and said bottom edges 4 act as a means for spacing such reinforcing from the sub-grade. In the concrete pouring process, the concrete will pass through said notches 5 and apertures 10. 20 This will form one continuous slab of concrete with a weakened vertical line of cleavage at the point where the form is used. This will cause any break which may occur in the slab due to expansion and contraction. 25 to follow the line of weakness. The portion of the slab which extends through said notches 5 and apertures 10, if broken, will break in an irregular plane, thus preventing the broken slab from any vertical movement 30 with reference to the portion from which it was broken.

Obviously, the invention is susceptible of embodiment in forms other than that which is illustrated in the accompanying drawings 35 and described herein, and applicable, for uses and purposes other than as detailed, and I therefore consider as my own all such modifications and adaptations and other uses of the form of the device herein described as 40 fairly fall within the scope of my invention.

Having thus described my invention, what is claimed and desired to be secured by Letters Patent, is:

1. A joint form for pavement, embodying 45 a thin strip of suitable material having a straight upper edge and having a longitudinal and continuous corrugation below and parallel to said edge, said strip having a plurality of spaced legs downstanding from and in a plane with its body, and outstanding means carried by some of said legs for rigidly supporting a tie bar laterally therethrough.

2. Organization as described in claim 1, 55 in which the supporting means is formed by a part of the leg turned outward and a portion of the outwardly turned part bent around said bar.

3. A joint form for pavement, embodying 60 a thin strip of suitable material having a straight upper edge and having a longitudinal and continuous corrugation below and parallel to said edge, a plurality of spaced legs, downstanding from and in a plane with 65 said strip, some of said legs having a vertical

corrugation for giving them strength, and means carried by other of said legs for rigidly supporting a tie bar laterally therethrough, said means formed by a part of the leg turned outward and a portion of the outwardly turned part bent around said bar.

4. A joint form for pavement embodying a thin strip of suitable material having a straight upper edge and having a longitudinal and continuous corrugation below and parallel to said edge, a plurality of spaced legs downstanding from and in a plane with said strip, some of said legs having a plurality of tie bars for lateral insertion through some of said legs, and means carried by some of said legs for rigidly supporting said tie bars laterally therethrough, said means formed by a part of the leg turned outwardly and a portion of the outwardly turned part bent around said tie bars.

5. A joint form for concrete embodying a strip of suitable material, said strip having a plurality of tie bars each extending at intervals laterally therethrough, and outstanding means for rigidly supporting said tie bars.

6. A joint form for concrete embodying a strip of suitable material, said strip having a plurality of tie bars each extending at intervals laterally therethrough, and outstanding means formed integrally with said strip for rigidly supporting said tie bars.

7. A joint form for pavement, embodying a thin strip of suitable material having a straight upper edge and having a longitudinal and continuous corrugation below and parallel to said edge, said strip having a plurality of spaced legs downstanding from and in a plane with said strip, outstanding means carried by some of said legs for rigidly supporting a tie bar laterally therethrough, and means also carried by some of said legs for permitting the introduction of concrete therethrough.
